(57) **CLAIM**

The ornamental design for a lottery ticket dispenser, as
shown and described.

DESCRIPTION

FIG. 1 is a perspective view of a first embodiment of a
lottery ticket dispenser according to our new design.

FIG. 2 is a front elevational view of the embodiment of FIG.
1.

FIG. 3 is a right side elevational view of the embodiment of
FIG. 1 with the opposite side being a mirror image thereof.

FIG. 4 is a rear elevational view thereof.

FIG. 5 is a bottom plan view thereof.

FIG. 6 is a top plan view thereof.

FIG. 7 is a perspective view of a second embodiment of a
lottery ticket dispenser including a mounting plate according
to our new design.

FIG. 8 is a front elevational view of the embodiment of FIG.
7.

FIG. 9 is a right side elevational view of the embodiment of
FIG. 7 mounted upon a vertical surface shown in phantom
for environment with the opposite side of the dispenser
being a mirror image thereof.

FIG. 10 is a rear elevational view thereof.

FIG. 11 is a bottom plan view thereof.

FIG. 12 is a top plan view thereof; and,

FIG. 13 is a cross-sectional view taken along line 13—13 of
FIG. 8 showing the dispenser and mounting plate mounted
upon the vertical surface for environment.

The broken lines in the drawings represent environmental
structure only and form no part of the claimed design.
